3 Claims. (Cl. 200—148)

1

This invention relates in general to gas blast circuit breakers.

Circuit breakers using compressed gas are already known in which at least one switch contact is moved relative to the other in the direction of flow of the compressed gas and in which at least one of the contacts is hollow. Circuit breakers with hollow contacts can be constructed for operation at the highest of voltages, since the arc from the beginning of its formation is subjected to a most favorable blowing action and is bathed entirely by compressed gas, the space between the contacts having a true compressed gas insulation. Circuit breakers constructed in this manner possess a most desirable arc extinction characteristic and may have very high power ratings in comparison to their size. For improving the circuit-breaking and for preventing a rapid rise in returning voltage following an extinction of the arc, resistance has been connected in parallel with the switch contacts. The method has been disclosed of connecting the resistance in circuit with a spark gap, the electrodes of the gap being located one behind the other in the blowing chamber which adjoins the switch contacts. Such an arrangement makes it possible to combine one electrode of the gap with the hollow switch contact with the result that a spark gap can be placed so near to the switch contacts that it is located in the range of a most favorable blowing action by the gas as it emerges from the mouth of the hollow contact. Furthermore, the distance between the electrodes of the arc gap is small and consequently the ignition and extinction characteristics for the spark gap are satisfactory.

The spark gap in the compressed gas circuit breaker acts at the same time as an excess voltage leak, when for instance an inductive circuit is to be broken, where excess voltages can make their appearance. In order to be able to effect an extinction of the arc in the spark gap even during phase opposition, the spark gap must have a good insulation characteristic, this affecting its protective effect in ordinary circuit-breaking.

This invention relates to a compressed gas circuit breaker with at least one hollow switch contact and with spaced electrodes forming a spark gap located in the blowing chamber adjoining the contact. This spark gap when bridged by an arc connects a protective resistance in parallel with the switch contacts, means being provided according to the invention by which the actuating or striking voltage of the spark gap is changed automatically during an opening op-

2

eration of the circuit breaker so that at the beginning of a circuit-breaking operation, the voltage required to bridge the arc gap is small but increases during the operation and is finally brought back to its original value upon completion of the operation.

In the drawings, Figs. 1 and 2 are vertical sections of two different constructional examples of circuit breakers embodying the invention.

10 Referring now to Fig. 1, the circuit breaker shown includes a pair of tubular insulating casings 1 and 2 which are separated by, and joined to, a hollow contact element 3.

The hollow contact element of the circuit breaker consists of an assembly which includes a member 4, a pair of telescoped conductive sleeves 5 and 6, an annular plate 8 secured to the bottom of sleeve 6 and a spring 10 positioned between the underside of fixed member 4 and the upper side of plate 8. Telescoped sleeves 5 and 6 fit snugly for good electrical contact, and these sleeves are integral with or secured to the contact member 4 and contact plate 8 respectively.

15 The fixed contact member 4 contains a central opening 11 therethrough which is tapered outwardly from the bottom to the top in nozzle form. The openings through sleeves 5 and 6, the opening 11 through contact member 4 and the opening 12 through plate 8 are all aligned so as to permit gas flow therethrough when the contacts of the circuit breaker separate.

20 The interior of casing 1 constitutes a blowing chamber 1a for the circuit breaker, part of this chamber also serving as a spark gap X defined by a pair of electrodes 13 and 14.

25 Electrode 13 is annular in form and is constituted by the mouth piece of an electrically conductive sleeve 15 which includes an upper cylindrical portion 16 and a lower tapered portion 17. A muffler 18 is disposed within the top of the cylindrical portion 16.

30 As is clear from the drawing, the outer diameter of the cylindrical portion 16 of sleeve 15 is substantially the same as the interior diameter 40 of casing 1 and the sleeve 15 is joined to casing 1 at the junction line between the upper and lower sleeve portions 16, 17. Gas pressure in the space between the inside wall surface of casing 1 and the outside wall of the tapered portion 17 of the sleeve 15 increases under the action of the gas blast and serves a function which will be explained in detail hereinafter.

35 Electrode 14 is a pin that is mounted for movement along the vertical axis of the circuit breaker. Pin 14 is slidable within a guide 19 of

conductive material, the outside surface of pin 14 being in good electrical contact with the inside surface of guide 19. Pin 14 moves downwardly against the action of a spring 20, which is carried within guide 19, as gas pressure in the blowing chamber 1a increases. Thus the length of the spark gap X will vary with the magnitude of the gas pressure. The lower portion of guide 19 terminates in an L-shaped tube 21, the end of which extends through the hollow contact member 4 to support the same and to provide a vent for the space beneath the pin 14.

One end of a resistance 22 is connected to a terminal 23 on sleeve 15 and hence is in good electrical contact with electrode 13 since sleeve 15 is made of electrically conductive material. The other end of resistance 22 is connected via terminal 24, a conductive casing 25 and conductive bracket 26 to a fixed contact 27 of the circuit breaker which normally is engaged with the spring loaded contact plate 8.

Connections from the line to the circuit breaker are made at line terminal 28 on conductive casing 25 and at line terminal 29 on the hollow contact member 4. From what has been described, it is now evident that resistance 22 and the spark gap X are arranged electrically in series and are connected across hollow contact member 4 and the fixed contact 27 of the circuit breaker.

When an opening operation of the circuit breaker is desired, pressure gas directed upwardly from any suitable source through casings 2 and 25 impinges against the bottom of the contact plate 8 causing the latter to rise and hence break the electrical connection between the plate 8 and fixed contact 27. Pressure gas flowing through the opening 12 in plate 8 and upwardly through the sleeves 5, 6 and through opening 11 surrounds the arc formed between the opening circuit breaker contacts on all sides and blows it upwardly. The discharged switch gases ionize the spark gap X rendering the same conductive and hence switching in the parallel connected resistance element 22 which improves the circuit-breaking operation. As the gas continues to flow through opening 11 in the hollow contact member 4, pressure of the gas in the blowing chamber 1a will increase causing progressive downward movement of the contact pin 14 which thus increases the length of the spark gap between the two electrodes 13 and 14.

If, during operation of the circuit breaker, excess voltage makes its appearance, the spark gap X acts as a leak inside of the circuit breaker. When the flow of pressure gas is terminated, the circuit breaker contacts 8 and 27 will close, and electrode pin 14 will be moved back to its original position by the restoring force of compressed spring 20 as the gas pressure in chamber 1a decreases.

In the Fig. 1 arrangement, it will accordingly now be obvious that the actuating or striking voltage of the spark gap X is accordingly adjusted by changing the distance between the two electrodes 13 and 14 as a function of the accumulated gas pressure in the blowing chamber 1a so that such voltage will be comparatively small at the beginning of an opening operation of the circuit breaker, the voltage increasing however, during circuit breaker operation and finally at the end of the operation of the circuit breaker being brought back to its original value. In this way, a certain protective action of the

spark gap is assured for circuit-breaking and as an excess voltage leak.

Referring now to the modified form of the circuit breaker shown in Fig. 2, it will be seen that the arrangement of parts is somewhat similar to that shown in Fig. 1; hence corresponding parts of the two circuit breaker constructions have been given like reference numerals but with primes added to the numerals used in Fig. 2 to distinguish between them. However, in the construction shown in Fig. 2, variation of the striking voltage of the spark gap during an opening operation of the circuit breaker is effected by a change in the accumulated gas pressure in the arc blowing chamber rather than by a change in the distance between the two electrodes which form the gap. Thus, in Fig. 2, the position of electrode pin 14' with respect to annular electrode 13' remains fixed since electrode 14' is secured rigidly to hollow contact 4'. A partition 31 containing a small opening 32 is placed transversely within the sleeve 15'. A throttle valve head 33 is normally held away from opening 32 by a spring 34 but during an opening operation of the circuit breaker, the initial increase of gas pressure in chamber 1a' causes valve head 33 to move upwardly and increase the resistance to flow of pressure gas through the opening 32, thus further increasing the gas pressure in chamber 1a' and likewise simultaneously increasing the striking voltage of the spark gap X'.

The invention can be used in compressed gas circuit breakers provided with multiple or compound circuit-breaking, in which a plurality of sets of switch contacts are aligned one above the other to form a series of separate arcs as the circuit is broken.

In both constructions illustrated, the resistance element paralleled with the contacts of the circuit breaker could be placed concentric with the blowing chamber instead of as a separate structural part beside the blowing chamber. A semi-conducting coating could moreover be employed as a resistance, or the blowing chamber wall itself could consist of semi-conducting resistance material.

I claim:

1. In a pressure gas operated circuit breaker, a pair of switch contact elements, one of which is hollow, an arc blowing chamber adjoining said hollow contact, means supporting said contact elements for movement relative to each other under action of pressure gas to break connection therebetween, first, and second spaced electrodes disposed in said chamber to define a spark gap, said first electrode being carried by said hollow contact and located in the path of the stream of pressure gas flowing therethrough, said second electrode being an annulus formed by the smaller end of a tapered sleeve set into and in contact with the wall of said chamber to form a pressure accumulating space between the exterior wall surface of said tapered sleeve and the interior wall surface of said chamber, a resistance connected in parallel with said switch contact elements through said arc gap, and means acting in response to a change in pressure of the gas in said chamber producing a corresponding change in the striking voltage of said spark gap.

2. A circuit breaker as defined in claim 1, wherein said first electrode is spring loaded for movement away from the other in response to a rise in pressure in said chamber during an opening operation of said circuit breaker, for increas-

ing the length of the spark gap from a predetermined value at the beginning of the opening operation and decreasing to said value upon completion of the opening operation.

3. A circuit breaker as defined in claim 1, 5 wherein said chamber includes an outlet for the escape of pressure gas from said chamber, and valve means responsive to a rise in pressure within said chamber for throttling said outlet, said valve means being disposed within said sleeve 10 on the downstream side of said second electrode.

HANS THOMMEN.
